UNITED STATES PATENT OFFICE.

JOHN B. SURPRISE, OF MEMPHIS, TENNESSEE.

PORTABLE FENCE.

SPECIFICATION forming part of Letters Patent No. 268,774, dated December 5, 1882.

Application filed June 3, 1882. (No model.)

To all whom it may concern:

Be it known that I, JOHN B. SURPRISE, a citizen of the United States, residing at Memphis, in the county of Shelby and State of Tennessee, have invented certain new and useful Improvements in Portable Fences; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

15 My invention relates to that class of fences known as "portable," and may be distinctively described as a "portable worm-fence."

The object of my invention is to construct a portable fence which shall combine the following advantages, to wit: first, be simple and inexpensive; second, be capable of erection and removal by sections with speed and facility; third, admit of free circulation of air about the points of contact of the ends of the 25 rails, and thereby lessen the chances of decay; fourth, be stable without the use of base-supports or stays. I accomplish this object in the manner hereinafter fully set forth and described.

30 In the accompanying drawings, Figure 1 represents the sections of the fence connected by clevises or U-shaped clamps; and Fig. 2 is a top view of the latter, showing the upright edges of the recessed rail ends beveled, for the purposes hereinafter specified.

Similar letters of reference indicate corresponding parts throughout the different views.

A B represent the adjacent rails of two panels of worm-fence, the top and bottom rails being rabbeted or notched at the ends to form for 40 each a corresponding recess and projection, and to fit together, as shown in the drawings. All the rails are connected together near their ends by strips or battens F.

H are U-shaped clamps, formed preferably 45 of metal, and driven down over the lapped ends of the top and bottom rails at the angles of their intersection, so as to bind or lock the two panels together, as shown in Fig. 1 of the drawings. The perpendicular edges of each of the rabbets are beveled at G to correspond with the inclination to each other of the rails.

The practical advantage of my invention is that it renders unnecessary the use of stays or other supports, while at the same time it forms 55 a cheap portable fence, and one which may be easily taken down or put up.

Having thus described my invention, what I claim is—

In a fence, the top and bottom rails, A B, 60 rabbeted and beveled, combined with battens F and clamps H, all constructed and arranged as shown and described.

In testimony whereof I affix my signature in presence of two witnesses.

J. B. SURPRISE.
